C. HEDMAN

DOOR

Filed Feb. 25, 1922

Inventor

Carl Hedman

Herbert E. Smith

Attorney

UNITED STATES PATENT OFFICE.

CARL HEDMAN, OF SPOKANE, WASHINGTON.

DOOR.

Application filed February 25, 1922. Serial No. 539,091.

To all whom it may concern:

Be it known that I, CARL HEDMAN, a citizen of Sweden (first papers having been taken out to become a citizen of the United States), residing at Spokane, in Spokane County, and State of Washington, have invented certain new and useful Improvements in Doors, of which the following is a specification.

10 My present invention relates to improvements in doors of the swinging type for use in houses as well as in other structures, and particularly applies to the construction of the door. The primary object of the invention is the provision of a door wherein the hanging style of the door is constructed and arranged in such manner as to co-act with the joint strip or strips of the door frame or casing to present a neat and workmanlike finish, to substantially close the joint between the door and its casing and thus eliminate any openings or cracks between the hinged door and its casing. By this construction the danger of children or others having their fingers caught between the door and its casing is eliminated, and an effectual seal is afforded at the joint regardless of the position of the hinged door. The invention further contemplates economy and facility in constructing the door and its hanging style, together with the construction of the door frame as will be hereinafter more fully pointed out and claimed.

35 In the accompanying drawings I have illustrated the adaptation of my invention to two forms of doors, and illustrated the parts as combined and arranged according to the best mode I have thus far devised for the practical application of the principles of my invention.

Figure 1 is a view in perspective of a swinging, panel door, which may be either a one-way door or a two-way door, having the hanging style which forms a feature of my invention applied thereto, and showing also one of the bearing or hinge plates for the door pintle.

Figure 2 is an enlarged view in perspective, showing a portion of a molding strip, one or two of which are used on the door casing in combination with the hanging style of the door.

Figure 3 is an enlarged view in perspective, showing a portion of a circular bead forming the hanging style of the door.

Figure 4 is a detail, horizontal, sectional view showing the relation of the door and its casing; the door being of the two-way swinging type.

Figure 5 is a similar view showing the invention as applied to the usual one-way door.

Figure 6 is a perspective view of one of the two hanging plates or pintle plates of the door.

Figure 7 is a perspective view of a fragment of the door at an upper corner illustrating the pintle plate and hanging style.

For convenience of illustration I have shown in Figure 1 a panel door 1, and indicating its rear edge as 2. At its rear edge is attached the hanging style 3, which as shown is a round or circular bead, preferably of wood, although it may be of other suitable material, and fashioned with its rear or outer face of arcuate shape. The bead may be fashioned in suitable lengths as stock material, on a machine, and is circular in cross section. In shaping the mold strip or bead, it is also grooved longitudinally to form a mortise 4, and this mortised bead is afterward cut to proper lengths corresponding to the height of the door upon which it is to be used as the hanging style. The mortised hanging style is fitted over the edge 2 of the door and may be secured thereto by nails, screws, or in other workmanlike manner. At the upper and lower ends of the style, and of course the top and bottom edges of the door, are provided bearing plates as 5, circular in shape to correspond with the cross section of the hanging style, and these bearing plates have arms 6, the arms and plates being attached as by screws to the door and its hanging style. Each bearing plate is fashioned with a central bearing opening 7 and the ends of the hanging style may be bored out as sockets forming continuations of these openings in the plates for the door pintles, not shown.

In Figures 4 and 5 the door casing is illustrated and indicated as a whole by the numeral 8, and it will be understood that the pintles or pivots for the door are alined in a vertical plane and project downwardly and upwardly with relation to the top and bottom edges of the door.

In combination with the arcuate hanging style of the door I utilize a casing strip 9 having a concave or curved edge 10. This strip is fashioned in a molding machine and

cut into lengths suitable for use in the door casing.

It will be apparent that the molding strip 9 is reversible or interchangeable for use at either side of the door. For instance in the one-way door of Figure 5 a single strip 9 is used at one side of the door, which door as shown by dotted lines is capable of swinging through an arc of 90°. When used with a two-way swinging door, as indicated in Figure 4 where the door may swing through an arc of 180° a second cut of the molding strip is used and designated 11 with its concave face 12. The two strips 9 and 11 are cut from the same molding and are properly positioned at the two sides of the door. The strip 9 of Figure 5 may readily be reversed as to position, and placed at the left side of the door in Figure 5, if desired. Whether a single strip or a double strip is used a channel is formed at the edge for the hanging style of the door that is effectually closed at the joint between the style and casing strip, and the strip or

strips form guides for the rotating hanging-style.

It will be evident that the bead 3 and the molding strip 9 may be constructed or fashioned at the mill at comparatively slight expense and kept in stock for use in constructing and hanging the door, and that both time and labor are saved in constructing and hanging the door.

Having thus fully described my invention, what I claim as new and desire to secure by Letters Patent is—

The combination with a door, of a hanging style circular in cross section and having a longitudinal mortise receiving an edge of the door, top and bottom circular bearing plates attached to said style and integral arms on said plates attached to the door; and a door casing having a molding strip formed with a concave face for engaging said style.

In testimony whereof I affix my signature:

CARL HEDMAN.
